UNITED STATES PATENT OFFICE.

ANTON GAREIS, OF POLA, AUSTRIA.

MARINER'S COMPASS.

SPECIFICATION forming part of Letters Patent No. 227,972, dated May 25, 1880.

Application filed April 20, 1880. (No model.) Patented in England March 1, 1879.

To all whom it may concern:

Be it known that I, ANTON GAREIS, hydrographer to the Imperial Royal Austrian Navy, a citizen of Austria, residing at Pola, in the Empire of Austria, have invented certain new and useful Improvements in Mariners' Compasses; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The present improvements in mariners' compasses have for their object a more convenient mode of removing and reinserting or replacing the cap or socket of the compass-card, as well as the pivot-pin on which the said card 20 rests, than is practicable in the ordinary construction of mariners' compasses.

These improvements are more especially intended for fluid or liquid compasses, but are also applicable to other kinds of mariners' 25 compasses.

The invention consists in the construction and combination of parts which will be hereinafter more fully described, and then set forth in the claims.

30 In the accompanying drawings, Figure 1 represents a liquid compass in vertical section, the "cardanic suspension" being omitted, but letters A A indicate the level in which it lies. Fig. 2 shows, in plan, the lifting device for 35 arresting the compass-card. Fig. 3 is a key or tool for removing the pivot-pin. Fig. 4 represents a modified construction of the pivot-pin.

According to the present improvements, the 40 upper glass cover, *t*, is provided with an aperture, in the center of which a capsule or box, *a'*, is fitted, communicating with the compass-box, and closed by a screw plug or valve, *a*, when the compass is in use. If the screw plug should be lost, any other suitable stopper 45 or an ordinary cork may be used.

The agate or sapphire cap *c* is secured in the holder *d d'*, and kept in position by means of the hollow screw *b*, the said holder being 50 screwed into the conical carrier *e e* of the com-

pass-card, and provided at the top with a projecting stud, *d'*.

A similar stud, *i*, is arranged on the lower part of the pivot-pin. The cap may also be set directly into the screw *b* and screwed with it into the holder *d d'*. The lifter or arresting device is provided with two or more teeth, *f f*, symmetrically distributed, and similar teeth project likewise from the lower edge of the carrier *e e* of the compass-card. 55

For removing the cap of the compass-card, as well as the pivot-pin, for the purpose of examining or changing them, the compass-card is raised from the pivot-pin by means of the lifter, and the capsule *a' a'*, which closes the 60 aperture of the cover, is opened. The key *h h'*, Fig. 3, is then inserted through this aperture, and being hollow at one end and provided with a rectangular slot, *h*, the hollow end fits over the top of the aforesaid holder *d d'*, or 65 over the lower shaft of the pivot-pin, while the slot *h* receives the stud *d'* or the stud *i*. By turning the key in the corresponding direction the serrated lower edge of the carrier *e e* of the compass-card will first engage with 70 the teeth *f f* of the lifter, thereby securing the compass-card, and then the holder *d d'* of the cap *c* may be screwed out of the carrier *e e*, and can be removed through the box *a' a'*. Through the opening thus formed 75

in the compass-card the pivot-pin *s* *i* can then be screwed out and removed by means of the same key *h h'*. On the opposite end, *h'*, the key is provided with an ordinary screw-driver for screwing off the hollow screw *b*. It will 80 be understood that both the key and the cap-setting, as well as the shaft of the pivot-pin, may be made of any suitable form. The reinserting of the pivot-pin and the cap is effected in like manner, and the capsule *a' a'* can then 85 be closed.

When the compass is not provided with a lifter for raising the compass-card the pivot-pin *s* may, as shown in Fig. 4, be fixed to a screw-plug, *k*, passing through the center of 90 the bottom *t'* of the compass-box, and can then be removed by turning the compass-box over and screwing out the said screw-plug *k*. When the pivot-pin *s* and its shaft *l* are removed the screw-plug *k* is reinserted. Then 95 100

the compass-box is again turned to its normal position, and the compass-card is held in position by its serrated carrier engaging with the teeth $f' f'$, provided on the flange $m m$. The changing of the cap is effected in the manner described with reference to the construction shown in Fig. 1. For reinserting the pivot-pin s the compass-box is afterward again turned over.

10 The screw-joint of the upper part, $p p$, of the cover $p p q q$ and the compass-box $B B$ is arranged above the level of the fluid, so that the latter, if rising to the level $n n$, cannot escape through the said joint. The space over the level $n n$ permits the fluid to expand under changes of temperature. The lower cylindrical part, q , of the cover of the compass-box, on which the lubber-line is indicated, extends below the level of the compass-card, and so forms an inner compartment, that prevents the access of bubbles of air from the top of the cover to the compass-card. Any bubbles of air which, nevertheless, may have formed may be removed by opening the aperture in the capsule $a' a'$, and causing 25 the bubbles to move toward the center of the cover to enable them to escape there. This result will be effected as long as the level of the fluid is higher than the under surface of the glass cover t . If this is no longer the case, 30 the deficiency of the fluid will be indicated by the cessation of the escape of the bubbles of air through the aperture in the capsule $a' a'$, and then so much additional fluid has to be poured into the compass-box through the said 35 aperture, or that of the screw-plug z , as will raise the fluid-level to about the upper surface of the glass cover. Both during the filling up of the compass-box and the removing of bubbles of air through the capsule $a' a'$ the screw- 40 plug z must be removed to permit the escape or allow the admission of air. The capsule $a' a'$ is arranged with its valve a so that the said valve need not close tightly, and it is provided with an aperture, o . After the plug z has been 45 screwed into its place the last remnants of the inclosed air and a small portion of fluid can escape through the aperture o in the part of

the capsule $a' a'$ above the valve, while closing the said valve, the screw-box of which is tightened by means of a leather packing to 50 prevent evaporation. Each time, before closing the valve a , the compass-box has to be inclined a little by elevating the side of the plug z to make the fluid-level rise in the aperture of the said valve. In this position of the compass-box the plug z is to be closed first, and then, after giving the compass-box its normal position, the valve can be closed, as above described. As already mentioned, the arrangements for removing the cap and pivot can be 55 used on other mariners' compasses besides fluid compasses.

The outer compass-box, $B B$, may, as shown by dotted lines in Fig. 1, be made of smaller diameter beneath the screwed part of the cover, 60 to reduce the weight of the entire compass, and also to permit contrivances for correcting or compensating the deviations of the compass-card, to be arranged near the same.

Having thus described my invention, what 70 I claim as new, and desire to secure by Letters Patent, is—

1. The compass-cover t , provided with a central aperture which can be opened for removing and replacing the cap and pivot-pin through 75 the same, and for removing any bubbles of air, substantially as described.

2. The combination of the compass-card carrier e , having bottom teeth, g , the lifter having teeth f , the removable cap-holder d , having 80 stud d' , the shaft of the pivot-pin provided with projection i , with the compass-cover, having a capsule and valve, and the key h , as and for the purpose set forth.

3. The compass-cover p , having a lower cylindrical part, q , extending below the level of the compass-card, substantially as herein set forth.

In testimony whereof I affix my signature in presence of two witnesses.

ANTON GAREIS.
